CLAIM

The ornamental design for personal golf ball and tee holder with a time display, as shown and described.

DESCRIPTION

FIG. 1 is a perspective view of a personal golf ball and tee holder with a time display showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view thereof, the opposite side being a mirror image of that shown; and,

FIG. 7 is a perspective view thereof, the broken line showing of a golf ball, tees, belt and time display is for illustrative purposes only and forms no part of the claimed design.
